UNITED STATES PATENT OFFICE.

DE VER H. WARNER, OF BRIDGEPORT, CONNECTICUT.

DESIGN FOR A CORSET.

SPECIFICATION forming part of Design No. 21,884, dated October 4, 1892.

Application filed July 7, 1891. Serial No. 398,722. Term of patent 14 years.

To all whom it may concern:

Be it known that I, DE VER H. WARNER, a citizen of the United States, residing at Bridgeport, Fairfield county, State of Connecticut, have invented a Design for a Corset, of which 5 the following is a specification.

My invention relates to a new and original design for corsets; and it consists in a corset having the ornamentation substantially as 10 hereinafter described, and as illustrated in the accompanying drawing, in which I have shown one section of the corset embodying my design.

The essential feature of the design consists 15 in a corset having on its surface the strips a, extending from the upper to the lower edge of the corset-section, and each edge of each strip is in the form of a rounded rib-like bead b, the whole having the appearance of a flat central strip having a rounded bead on each 20 side and presenting an ornamental and finished appearance.

What I claim is—

The design for a corset, substantially as described and shown. 25

In testimony whereof I have signed my name to this specification in the presence of two subscribing witnesses.

D. H. WARNER.
